WELL PUMPING DEVICE

Robert Alexander Wilson and Roy Alvah Smith,
Dallas, Tex., assignors to Kibele Manufacturing
Company, Dallas, Tex., a corporation of Texas

Application November 24, 1936, Serial No. 112,444

8 Claims. (Cl. 103—5)

The invention relates to devices for lifting liquids from wells and has particular reference to the construction and operation of combined stages of mechanical fluid lift and air lift devices.

The centrifugal type of pump for pumping oil from wells has certain advantages. However, in the production of oil from deep wells this type of pump has certain limitations since its efficiency drops rapidly when a certain limited head is exceeded. The primary object of the invention is to provide means for pumping oil from deep wells by a combination and arrangement of centrifugal pumping means and air lift means whereby a centrifugal pump will lift the oil in the well through a distance for which such pump operates efficiently and where an air lift will supplement the centrifugal pump to effectively lift the oil the remaining distance to the surface. With this combination each pumping unit may be made to operate effectively within a range of high efficiency and a high over-all efficiency may be obtained.

Another object is to provide a pumping system in which the fluid is pumped from the lower levels of a well through a flow tube and thence flows into the well casing for air lifting in the upper levels of the well.

Still another object of the invention is to provide a packer connection between the mechanical and the air lift stages of pumping, in which connection the mechanically pumped fluid is introduced into the well casing at a level above the level of introduction of the pumping fluid.

It is a further object of the invention to provide a pumping device wherein a frangible barrier is provided at the junction of the pumping stages whereby the barrier may be destroyed to admit introduction of a wire line tool below such junction.

Other objects, together with the foregoing, will be apparent as recited in the novel features of construction, combination and arrangement of parts hereinafter more fully described and particularly pointed out in the appended claims, reference being had to the accompanying drawing forming a part of this specification and in which:

Fig. 1 is a sectional view showing the positions occupied by the parts of the device of the invention when installed in a well, section being taken on the line 1—1 of Fig. 3.

Fig. 2 is a longitudinal section of the device taken at right angles to the section of Fig. 1.

Fig. 3 is a transverse section of the device of the invention taken on line 3—3 of Fig. 1.

Fig. 4 is an assembly view partly in section showing the complete apparatus in the well.

Referring now more particularly to the drawing wherein like numerals of reference designate similar parts in each of the figures the numeral 1 designates the well casing in which is placed the device of the invention. Reference is particularly directed to Fig. 4 in which the device of the invention is illustrated as a complete assembly installed in a well. The well casing is provided with a casing head which is generally designated as 13. This casing head is of usual construction except that it is provided with an opening having a gland 42 through which passes an electric cable 41, which cable carries electrical energy into the well to drive the centrifugal pump 12. Fluid is carried upward from pump 12 through flow pipe 5 to a connector 3 above a packer 4 which seals the annular space between the casing 1 and the tube 5.

The connector generally designated as 3 is herein referred to as a stage connector in that it serves as the junction between pumping stages as will be made apparent as the description proceeds. Stage connector 3 is so constructed and arranged that the fluid pumped upwardly through flow pipe 5 is admitted to the annular space within casing 1 above packer 4.

Extending downwardly from the surface to the stage connector 3 is a tubular member 39 which carries a pumping fluid to the well. This member 39 terminates in the stage connector 3 in which the pumping fluid is likewise admitted to the annular space within the casing 1 and above the packer 4.

By referring to Figs. 1 to 3 it will be seen that within the casing 1 is flow tube 5 which is attached to a packer tube 7. Between the packer tube 7 and the casing 1 is provided a packer generally designated as 4, the purpose of which is to seal the annular space about the tube. The packer tube 7 is in turn attached to the stage connector 3. The entire assembly thus generally described is supported from the top of the well through tube 39 which, as has already been pointed out, serves also to supply pumping fluid to the oil that is discharged into the casing above packer 4.

The flow pipe 5 carries fluid upwardly from the pumping means 12. To this flow pipe is attached packer unit 4 which includes packer tube 7 which is directly connected to pipe 5 to provide a bore 6 for continuous flow of pumping

fluid therethrough. Mounted upon and secured to member 7 is a collar 8 which supports a flanged ring 9, the flanges of which taper inwardly from their edges as shown at 10. Within ring 9 is positioned a packing ring 15, preferably of rubber. This ring is expanded into sealing position by a collar 16 which is positioned on the tube member 7 coaxially with the packing ring 15. A second flanged ring 17 which is similar to ring 9 is mounted upon collar 16 and is provided with a second packing ring 18. Collar 19 is positioned within packing ring 18.

Stage connector 3 is threadably secured to packer tube 7 at 11 and through this connection serves the dual function of connecting the elements of the pumping stages and also applying pressure to the packer members mounted upon collar 8.

The stage connector 3 is of particular construction and is essentially an enlargement in the tubular construction leading upwardly from the pump 12. The central bore 6 is provided with threads 11 and 14 in order that the connector may be threadably connected in the string of tubing in the well. Within the bore 6 and in the connector 3 is provided a shoulder 25 and adjacent threads 26. A disc 27 of frangible material is positioned within the shoulder 25 and is held securely in place by ring 28 which is screwed into the threads 26. This frangible ring serves as the barrier against continued upward flow of oil in the bore 6 and is made of frangible material in order that it may be broken by impact to admit a wire line tool to the lower levels of the well, as is well known in the art.

A plurality of openings 30 in the wall of the bore 6 below disc 27 lead obliquely upwardly through a passage 31 to the annular space surrounding connector 3. In a similar manner a plurality of openings 32 in the walls of the bore 6 above disc 27 lead obliquely downwardly through a passage 33 to the annular space surrounding the connector 3. The openings of these series are in circumferentially spaced relation, hence leaving metal fins 22 between passages 31 and 33.

It is to be noted that, as clearly shown in Fig. 3, the respective passageways 31 and 33 are not symmetrically spaced about bore 6. This minor lack of symmetry is made necessary through a longitudinal groove 40 in which is positioned an electric cable 41. This cable comprises insulated wires 42 to carry electrical energy from the surface to the pump 12 submerged in the fluid in the well. The cable 41 passes through a suitable opening in the respective elements of the packer 4, adequate sealing therebetween being provided.

The gas or air inlet pipe 39 is threadably attached to the upper end of the stage connector unit described and serves to support the unit and introduce pumping fluid for the air lift stage. An important feature of the invention is the automatic setting of the packer in the casing 1. This automatic setting takes place by virtue of the fact that when gas is applied the packer automatically expands to effect a seal with the casing. On the other hand, when the pressure is discontinued the packer releases and permits withdrawal thereof from the well casing. It should be also noted that the packer eliminates threading of the cable through the inside of the tubing thus leaving the bore of string of pipe open, except for frangible disc 27, and hence it is possible to insert fishing tools in case of parting of the tubing.

The operation of the device is as follows: Fluid

is pumped upwardly from the lower levels of the well by means of an electric pump through flow pipe 5. This fluid is discharged through openings 36 into casing 1. At the same time a gaseous fluid is pumped downwardly through pipe 39 and passageway 33. From the construction described it is apparent that this pumping fluid enters the annular space in the well bore at a level slightly below that at which the oil from the flow tube 5 enters the same annular space. This feature 10 is of importance for not only does the oil discharging from openings 36 possess an upward velocity but also the pumping fluid is introduced into the oil from beneath whereby turbulence is minimized and considerable energy of the velocity head is conserved.

In the preferred embodiment disclosed for purposes of illustration an electrically driven pump 12 has been provided. It is understood that the invention is not confined thereto because it is apparent that a reciprocating type of pump may be used. The sucker rod in such case passes through a suitable seal in frangible disc 27. It is also apparent that for the mechanical stage of pumping a suitable fluid actuated pump may be employed to lift the fluid through the lower levels of the well.

The drawing and description present what is now considered to be a preferred form of the invention by way of illustration only while the broad principle is accomplished by the means defined by the appended claims.

The invention claimed is:

1. In a well pump in combination a well casing, a tubing therein, a centrifugal pump secured to the lower end of said tubing, a packer between said casing and tubing above said pumping mechanism, a barrier in the bore of said tubing above said packer, said tubing having passageways from the bore below and above said barrier outwardly into the well casing whereby fluid from said pumping mechanism is delivered into the casing above the packer and a pumping fluid introduced into the tubing above said barrier lifts the pumped fluid upwardly from the packer.

2. In a well pump in combination a tubing within the well, pumping mechanism secured to the lower end of said tubing and adapted to pump liquid upwardly therein, a packer about said tubing to seal the space between the tubing and the well bore, a barrier in the bore of said tubing above said packer, said tubing having passages extending upwardly from the bore below said barrier to the annular space above said packer and other passages extending downwardly from the bore above said barrier to the space above said packer.

3. Apparatus for removing fluid from wells comprising a tubular pressure line extending downwardly into the well, said tubular line having radial downwardly extending passages adjacent the lower end thereof, a flow tube connected to said tubular line at the lower end thereof and extending downwardly into the well, said flow tube having radial upwardly extending passages adjacent its upper end, a barrier between the inner termini of said upwardly and said downwardly extending passages a pump at the lower end of said flow tube for pumping fluid therethrough and a packer about said flow tube below the openings therein.

4. A stage connector comprising a tubular member having a shoulder in the bore thereof, a frangible disc and means for holding said disc positioned in said bore against said shoulder, said

- tubular member having passages extending upwardly and outwardly from the bore below said 5
frangible disc and other passages extending downwardly and outwardly from the bore above said disc.
5. A pump including a well casing, a casing head thereon, a tubing supported in said casing, a packer on said tubing intermediate its ends, an electrically operated centrifugal pump on said 10
10 tubing below said packer, a barrier in the tubing above the packer, said tubing having radial passages diagonally upwardly and downwardly from below and above said barrier, respectively, and an electric cable extending downwardly between the 15
15 casing and tubing to said pump, and sealably passing through said packer.
6. In combination, a well casing, tubing within said casing, an electrically driven centrifugal pump secured to the lower end of said tubing to 20
20 elevate fluid within the tubing, an electric cable passing downwardly within said casing to said pump, a packer between the tubing and casing sealing the annular space therebetween above the pump and forming a seal about said cable, a barrier in said tubing above said packer, and openings 25
25 in the tubing above and below the barrier so that a lifting fluid may be introduced into the liquid exhausted into the casing through the openings below the barrier and above the packer.
- 30 7. In a device for lifting liquid in wells, the combination of pump means positioned within the well bore for reducing the static head of liquid to reduce the pressure exerted on the producing formation by discharging the liquid up- 30
wardly therefrom, a flow tube extending upwardly from the pump means, said tube having openings at a predetermined level so that the liquid may discharge outwardly into the well bore about the tube, a packer surrounding the tube below 5
said openings to form a seal with the well bore, and means for discharging a pressure fluid from within the tube and below said openings for aerating the liquid column above the packer to reduce the static head of the discharged liquid and lift 10
the liquid from the well.
8. In a device of the class described the combination of a well casing, a flow tube within said well casing, an elastic packing surrounding the flow tube in the well intermediate the ends thereof, power means for delivering liquid from the lower end of said tube therethru to an elevation above said packing in the casing, said packing being expandable under fluid pressure of the delivered liquid axially of the flow tube to move 20
20 the material of the packing into sealing engagement with the flow tube and said well casing, support members mounted on the flow tube to restrain the packing from movement axially thereof, aligned openings in said packing and support members, and a cable to supply power for said first means and extending longitudinally of the flow tube and passing thru said aligned openings and in sealed engagement 25
25 with the packing material surrounding the openings when the packing is subjected to the pressure of the liquid above it.
